CLAIM

The ornamental design for an ultrasound finger probe, as shown and described.

DESCRIPTION

FIG. 1 is a top perspective view of an ultrasound finger probe in an embodiment;

FIG. 2 is a bottom perspective view of the ultrasound finger probe of FIG. 1;

FIG. 3 is a first side view of the ultrasound finger probe of FIG. 1;

FIG. 4 is a second side view of the ultrasound finger probe of FIG. 1;

FIG. 5 is a top view of the ultrasound finger probe of FIG. 1;

FIG. 6 is a bottom view of the ultrasound finger probe of FIG. 1;

FIG. 7 is a front view of the ultrasound finger probe of FIG. 1; and,

FIG. 8 is a rear view of the ultrasound finger probe of FIG. 1.

The broken lines immediately adjacent the shaded areas represent the bounds of the claimed design while all other broken lines are directed to environment; the broken lines form no part of the claimed design.
